Des. 182,022
Patented Feb. 4, 1958

182,022

COMBINED SOFA BED, TABLE, AND DESK

Louis Elliott Frey, Los Angeles, Calif.

Application July 22, 1957, Serial No. 47,033

Term of patent 14 years

(Cl. D5—4)

Fig. 1.

Fig. 2.

Fig. 3.

Fig. 1 is a perspective view showing a combined sofa bed, table and desk embodying my new design in closed position;

Fig. 2 is a perspective view of the same in open position;

Fig. 3 is a rear elevational view.

I claim:

The ornamental design for a combined sofa bed, table and desk, substantially as shown.
